UNITED STATES PATENT OFFICE.

FRANKLIN D. PATTEN, OF PORTLAND, OREGON.

FEED-WATER HEATER FOR BOILERS.

1,121,755.

Specification of Letters Patent. Patented Dec. 22, 1914.

Application filed March 5, 1914. Serial No. 822,676.

To all whom it may concern:

Be it known that I, FRANKLIN D. PATTEN, a citizen of the United States, residing at Portland, in the county of Multnomah and State of Oregon, have invented certain new and useful Improvements in Feed-Water Heaters for Boilers; and I do declare the following to be a full, clear, and exact description of the invention, such as will enable others skilled in the art to which it appertains to make and use the same.

This invention relates to improvements in boilers and more particularly to attachments for heating the feed water before the same is injected into the boiler.

The primary object of the invention is to provide a device of the character described, which may be located in the breeching of a boiler and which, when in this position, will be subjected to a great amount of heat which would otherwise escape without being utilized.

A secondary object of the invention is to construct the attachment in such a manner as to cause a continuous circulation of water through the same, thus obviating any danger of overheating.

Still another object is to provide means whereby any sediment may be readily exhausted from the heating coil of the device.

With the above objects in view, the invention resides in certain novel features of construction and combination herein described and claimed and shown in the drawings wherein:

Figure 1 is a side elevation partly in section, of a return tube boiler showing the application of my invention within the breeching thereof; Fig. 2 is a vertical transverse section on the line 2—2 of Fig. 1; Fig. 3 is a horizontal section on the line 3—3 of Fig.

1; and Fig. 4 is a side elevation partly in section showing the application of the invention to a different form of boiler.

In the accompanying drawings, the letter B designates broadly a return tube boiler which comprises the usual water chamber C through which the return tubes T extend, a fire box F, above a suitable grate G, an ash pit P below said grate, a draft flue D extending beneath the major part of the water chamber C and rising in front thereof in communication with the tubes T, a breeching or smoke receptacle B' in com-

munication with the opposite ends of said tubes and a suitable stack S discharging from said breeching.

Within the breeching B' is disposed my improved feed water heater which is in the form of a horizontal coil 1 rigidly supported upon suitable brackets 2 which are secured to the opposite side walls of said breeching. The inlet end 3 of the coil 1 passes through one side of the casing around the breeching B' and is connected by means of a T-coupling with a feed pipe 5 and with a circulating pipe 6, the latter depending from said T-coupling, and thence extending horizontally as shown at 7 and entering the bottom of the water chamber C at the point 8. The horizontal portion 7 of the pipe 6 is provided with a check valve 9 which opens outwardly from said water chamber C and with a suitable globe or cut off valve 10. The feed pipe 5 is connected in any appropriate manner with the injector (not shown) and is preferably provided with a suitable cut off valve 11. The discharge end 12 of the coil 1 passes through the opposite side of the casing surrounding the breeching B' and is connected by a T-coupling 13 with a blow off pipe 14 and with a circulating pipe 15, which, like the circulating pipe 6, has its lower portion extending inwardly, in a horizontal plane as shown at 16 and in communication with the interior of the boiler at the point 17. The horizontal portion 16 is provided with a check valve 18 which opens toward the discharge end of the pipe 16 and with a globe valve 19, while the upright portion 15 is provided with a suitable stop cock 20 and with a globe valve 21. The blow off pipe 14 is provided with a suitable globe valve 22 for a purpose to appear.

The operation of the invention, so far described, is as follows: All of the valves and cocks, with the exception of the globe valve 22, are opened, and the water, flowing from the injector, will pass through the pipes 5 and 6 until the check valve 9 is closed by the pressure of said water, whereupon it will be forced through the coil 1 where it will become heated and from which it will be discharged through the pipe 15 and the check valve 18 therein and will then enter the lower side of the boiler at 17. When the supply of water is cut off, however, the

weight of the water within the boiler and the pressure of the steam therein, will cause the check valve 18 to close while the check valve 9 will be opened and the water will 5 rise within the pipe 6 and pass into the coil 1 where it will again be heated. Since the flow of the water from the coil, through the pipe 6, is automatically cut off by the check valve 9, said water will be forced to travel 10 through the pipe 15 and the check valve 18 and back into the boiler. This operation is continuous as long as the valves 10, 19, 20 and 21 are open, and as long as the valve 22 is closed. When, however, it becomes 15 necessary to cleanse the interior of the coil 1, it is simply necessary to close the stop cock 20 or the globe valve 21 and open the valve 22, whereupon, the return communication from the coil 1 and the lower side of 20 the boiler will be cut off and communication will be established between said coil and the blow-off pipe 14 through which the water will now be discharged, thereby removing any 25 sediment which may have collected in said coil. The globe valves 10, 18 and 21 are provided more for the purpose of regulating the amount of water to be circulated than for the purpose of using them to entirely prevent said circulation.

30 In Fig. 4, I have shown my invention as applied to a slightly different form of boiler B', which is provided on its under side with a mud tank or receptacle R with which the discharge end 17' of the horizontal portion 16' of the circulating pipe 15' communicates, said pipe 16' being provided with a check valve 18' and a globe valve 19', the operations of which are the same as that of the valves 18 and 19 above described.

35 The remainder of the construction is precisely the same as that illustrated in the first three figures of the drawings, and further description and illustration thereof is not thought to be necessary.

40 I have shown my invention as applied to two types of boilers, but it will be readily understood that I need not be limited to these particular applications, since the invention would operate to equal advantage 45 with any form of boiler having a breeching

adaptable for the herein mentioned purposes.

From the foregoing description, taken in connection with the accompanying drawings, the construction and operation of the 55 invention will be readily understood without requiring a more extended explanation. It may be well, however, to give a detail explanation of the manner in which the blow off pipe is employed. In using this 60 pipe, one of the valves 20, 21 or 19 is closed while the valve 22 is opened, thus preventing water, forced through the pipe 6 and the coil 1 from returning to the boiler, the result being that this water is forced to discharge through the blow off pipe 14 thereby 65 scavenging the coil 1 and also removing any mud or sediment from the boiler.

Having thus described my invention, what I claim as new and desire to secure by Letters-Patent, is:

The combination with a boiler having a smoke box in one end, a number of smoke flues communicating with the lower portion of said smoke box, and a smoke stack leading from the smoke box, of a pair of supporting brackets secured to the end walls of said smoke box, a horizontal coil of pipe rigidly supported upon said brackets directly beneath said stack and extending entirely across the smoke box, whereby all heat escaping through the stack is forced to travel between the various pipes forming the coil, circulating pipes connected to the opposite ends of said coil and discharging 85 into the bottom of said boiler, a check valve and a control valve in the opposite circulating pipes, a water feed pipe in valved communication with one end of said coil and a blow off pipe in valved communication with 90 the opposite end thereof, one of said check valves opening toward said coil and the other opening away therefrom.

In testimony whereof I have hereunto set my hand in presence of two subscribing witnesses.

FRANKLIN D. PATTEN.
